UNITED STATES PATENT OFFICE.

DAVID A. POOL, OF MACEO, KENTUCKY.

AUTOMATIC TRAIN-ORDER CRANE.

1,141,411.

Specification of Letters Patent. Patented June 1, 1915.

Application filed October 3, 1914. Serial No. 864,752.

To all whom it may concern:

Be it known that I, DAVID A. POOL, a citizen of the United States, residing at Maceo, in the county of Daviess and State 5 of Kentucky, have invented a new and useful Automatic Train-Order Crane; and I do hereby declare the following to be a full, clear, and exact description of the invention, such as will enable others skilled in the art 10 to which it appertains to make and use the same.

This invention relates to the art of delivering devices, and particularly to an improved automatic train order crane.

15 As an object of the invention it is the aim to provide means whereby as a train order loop with the order attached is detached, the crane is automatically thrown back from a close position to the train.

20 Another object of the invention is the provision of a reel carrying a plurality of detachable train order carrying loops, and as each detachable train order carrying loop is detached from the reel, a spring tensioned 25 cylinder actuates a lever, which in turn disconnects a latch member, thereby allowing the crane to automatically return to its normal position, by virtue of the resiliency of a spring. Said crane is designed to be manually 30 thrown into a position in close proximity to the train, when it is desired to dispose or arrange an order, so as to be taken by the engineer in the cab.

The present method of delivering train 35 despatches and other orders is accomplished by the station keeper or other employee of the road standing close to the fast moving train and holding a train order loop including an order or despatch in a position so as 40 to be grasped by the engineer.

The present invention particularly prevents the station keeper from being placed in such a dangerous position, at the same time insures the order loop being firmly held 45 in close position to the fast moving train.

In practical fields the details of construction may be subjected to alterations falling within the scope of what is claimed.

The invention comprises further features 50 and combination of parts, hereinafter set forth shown in the drawings and claimed.

In the drawings:—Figure 1 is a view in side elevation showing the movable part of the crane in its normal position. Fig. 2 is a 55 vertical sectional view, illustrating train or-

der loop carrying reel in elevation, and showing the crane adjusted closer to the cab of the engine. Fig. 3 is a sectional view on line 3—3 of Fig. 1, showing parts in elevation. Fig. 4 is a plan view of the loop carrying reel showing the movable crane in section, illustrating the structure of the spring tensioned cylinder in the tubular crane. Fig. 5 is a detail view of one of the order carrying loops, and a portion of the reel, showing the supporting arm for the loop to prevent the reel from turning through the action of the spring of said cylinder. Fig. 6 is a view in side elevation, showing a gravity actuated cylinder for the 70 reel, so that three successive train orders or despatches may be delivered to respective trains, before the gravity member actuates the latch, in order that the crane may return to its normal position, otherwise the crane 75 is constructed similar to that shown in Fig. 1. Fig. 7 is a sectional view through the tubular crane showing the gravity actuated cylinder.

Referring more especially to the drawings 80 1 designates a base member, and rising upwardly therefrom is a column or standard 2. This column or standard may be hollow or solid, just as required, and its upper portion is provided with an enlargement 3.

Extending laterally from opposite sides of the enlargement are tubular ears 4.

Telescoping horizontally through the tubular ears are the side portions 5 of a slide 6, which in plan view is U-shaped. 90

The sides 5 of the U-shaped slides extend upwardly as shown at 7, and terminate at horizontally disposed portions 8 which are suitably anchored in the laterally extending tubular ears 9 of the base 10 of the 95 tubular crane 11.

An operating lever 12 is pivoted at 13 to the base 1 as shown.

A bar 14 has its lower angular end secured at 15 in any suitable manner in the 100 lower portion of the column or standard 2. The bar 14 merges into a U-shaped portion 16. That is, this portion 16 is U-shaped in side elevation, and it straddles the slide 6, as shown clearly in Figs. 1 and 2. The upper portion 17 of 16 overlies the enlargement 3 of the collar or standard 2, and has a bearing plate 18 secured thereto.

The operating lever 12 has a handle end 19, while its lower U-shaped or forked por- 110

tion 20 extends through the slide 6 and straddles the U-shaped loop 16.

A link 21 is pivoted to the upper portion of the U-shaped part 20 of said lever upon each side. Each link 21 has a forked end 22, designed to engage or arch the forward portion of the slide, that is, the transverse part 23.

A link 24 has a pivotal connection 25 adjacent the base of the handle end of the lever 12, which link is in turn pivoted at 26 to a lug 27 of the base of the tubular crane.

A leaf spring 28 secured at 29 to the bar 14 is provided, and is designed to bear against the operating lever 12, so as to hold the lever and the tubular crane in their normal positions as shown in Fig. 1. It will be observed that by throwing the lever 12 in the direction of the arrow *a*, the tubular crane will be moved in a similar direction, owing to the link 24 pushing against the base of the crane, in which case the slide 6 will likewise be moved, and when the tubular crane is thus operated, the hook member 25 30 will engage the latch 31, which is pivoted at 32 in the bearing member 18, thereby holding the tubular crane in position against the action of the leaf spring 28. When the latch member 31 is disconnected from the hook 30, the lever 12 will be automatically thrown to its normal position, and owing to the provision of said links, 21 pushing against the U-shaped slide 6, the tubular crane will be correspondingly returned to its normal position. A key 34 is passed through openings of the upper and lower parts of the U-shaped portion 16 of the bar 14 so as to prevent the slide 6 from being reciprocated, there being a suitable padlock 35 or other arrangement or device connected to the lower end of the key so as to prevent its removal. A U-shaped loop or eye 36 is carried by the latch 31.

Surrounding the tubular crane is a split collar 37 held in place by the bolt 38, which passes through the ears 39 of said collar. Secured between the ears 39 of the collar by said bolt 38 is an arm 40 having a curved extension 41, the upper portion of which 45 terminates in a T-shaped part 42. A shaft 43 is mounted in bearings of the tubular crane and on one end of the shaft a reel 44 is journaled to rotate with the shaft. Also on the shaft but located within the tubular crane is a drum or cylinder 45, which is under tension of the spring 46, which is coiled about the shaft, and so connected to the drum and the interior wall of the crane, as to tend to rotate the reel and drum in the 50 direction of the arrow *b*. This drum 45 is provided with projections 47, there being adjoining cam surfaces 48, any one of which is designed to engage the arm 49 of the angular lever 50, which is pivoted at 51. The 55 arm 52 of the angular lever 50 extends

through the eye or loop 36. When the tubular crane is in a position out of registration or alinement with the column or standard 2 or in close position to the train, and one of the cam surfaces in contact with the arm 49 of said lever 50, and an order or despatch loop 53 is removed from the reel 44, the action of the spring 46 will cause the drum to rotate in the direction of the arrow *b*, the cam surface and the projection 47 acting to rock the lever 50, causing the arm 52 to raise the latch 31, thereby releasing the hook 30, and through the action of the spring 28, the operating lever 12 and the tubular crane 11 will be automatically returned to normal position.

The reel 44 is provided with U-shaped radial spokes 55, that is, they are U-shaped in plan view, and upon pins 56 of said spokes T-shaped dogs 57 are pivoted. 85 These dogs are held in contact with the shanks 58 of the order loops 53 by the springs 59. The shanks 58 of the order loops are received in sockets 60 of said reel, while the bodies 61 of the shank rest upon the T-shaped end 42 of the curved portion 41 of the arm 40, thereby holding the reel against rotation in the direction of the arrow *b* and against the action of the spring 46. However, just so soon as an order loop 95 together with its order or despatch 63 is removed by the engineer in the cab or locomotive, said reel makes a third revolution through the action of the spring 46, thereby actuating the angular lever 50, which in turn 100 releases the latch 31, thereby allowing the crane to return to its normal position. It may be that the next train requires no despatches or orders, therefore, for this reason the crane is returned to its normal position, 105 thereby avoiding the possibility of the next train receiving a despatch, which is not intended for the crew of the train. However, the third train should receive its orders or despatches, in which case the station keeper 110 or other employee operates the lever 12, throwing the crane in position, so that the next order loop may be detached.

The upper end of the tubular crane is provided with a suitable top or cover 66, which 115 carries an angular bracket 67, having a hook, 68, for the support of the usual signal lantern or the like 69, thereby not only notifying the engineer that a despatch or order is intended for his crew, but also enabling him 120 to plainly see that the order loop is in position ready to be removed or snatched. The angular bracket 67 is provided with a downwardly extending angular arm 70, which may support a lantern or the like.

It may be necessary that the station keeper may desire to deliver three successive orders or despatches either to a single train, that is, one to the engineer, one to the conductor, and one to the trainman or brake- 130

man; or it may be necessary to deliver three successive orders or despatches, one to each of three different trains. To accomplish the delivery of three successive despatches or 5 orders the cylinder 45 is actuated by a gravity member 72 having a cable passing about said cylinder, instead of the employment of the spring 46. This gravity member or weight 72 is arranged at a sufficient height 10 above the arm 74 of the latch 31 as shown in Fig. 6 so as to contact with said arm 74 after the three successive orders or despatches have been removed. When the weight or 15 gravity member contacts with the arm of said latch the hook 30 is released, thereby allowing the lever 12 and the tubular crane to resume their normal positions.

The invention having been set forth what is claimed as new and useful is:—

- 20 1. In a despatch delivering apparatus, a crane, a revoluble spring tensioned reel having radially extending spokes and provided with detachable despatch holding loops, a spring tensioned T-shaped dog carried by 25 each spoke to clamp the shank of the loop in position on the spoke.
2. In a despatch delivering apparatus, a crane, a revoluble spring tensioned reel having radially extending spokes and provided 30 with detachable despatch holding loops, a spring tensioned T-shaped dog carried by each spoke to clamp the shank of the loop in position on the spoke, means to support the shank of the loop to hold the reel against 35 rotation by the spring tensioned means.
3. In a despatch delivering apparatus, a crane, a revoluble spring tensioned reel having radially extending spokes and provided 40 with detachable despatch holding loops, a spring tensioned T-shaped dog carried by each spoke to clamp the shank of the loop in position on the spoke, means for removing the crane to a lateral position closer to a 45 train, a device for holding the crane in such position, said spring tensioned means of the reel mechanism including means having connections to actuate said device to release the crane, and means for returning the crane to its normal position.
- 50 4. In a despatch delivering apparatus, a supporting column having guide ears, a U-shaped slide mounted in said ears, a bar connected to the column and having a U-shaped portion straddling said slide, a latch on the

U-shaped portion, a crane including a 55 mechanism for holding a plurality of despatch holding loops, and supported upon the slide, connections between the crane, and the slide, including a spring tensioned operating lever in said connections, for moving 60 the crane and the slide laterally, a device on the lever to be engaged by said latch to hold the crane and the lever in an adjusted position, said mechanism of the crane including means having connections to actuate the 65 latch to release the lever, as a despatch holding loop is detached.

5. In a despatch delivering apparatus, a supporting column having guides thereon, a slide mounted in the guides, a bar connected 70 to the column having a loop portion receiving said slide, a latch on the loop portion, a crane including a mechanism for holding a plurality of despatch holding loops and mounted upon the slide, connections between 75 the crane and the slide, an oscillatory member in the connection for moving the crane and the slide laterally, said oscillatory member having means to be engaged by said latch to hold the crane in an adjusted position, and means actuated by said mechanism to operate the latch to release said oscillatory member, as a despatch holding loop is detached.

6. In a despatch delivering apparatus, a 85 supporting column having guides, a slide mounted in the guides, a crane including a mechanism for holding a plurality of despatch holding loops and mounted upon the slide, connections between the crane and the 90 slide including a spring tensioned oscillatory member for moving the crane and the slide laterally, a device on said member, means to automatically engage said device to hold the crane and the slide in a lateral position 95 against the spring tensioning means of said member, and means actuated by said mechanism for operating the holding means of said device to release the oscillatory member, as a despatch holding loop is detached. 100

In testimony whereof I have signed my name to this specification in the presence of two subscribing witnesses.
